CLAIM

The ornamental design for a barbecue grill as shown and described.

DESCRIPTION

FIG. 1 is a perspective view of the barbecue grill in accordance with my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a perspective view thereof, in a condition of use. The dotted line portions show unclaimed subject matter only and form no part of the claimed design.

1 Claim, 7 Drawing Sheets

FIG. 5

FIG. 4
